UNITED STATES PATENT OFFICE.

JOHN W. GLEASON, OF SCHENECTADY, NEW YORK.

SPARK PLUG.

Application filed February 19, 1920. Serial No. 359,945.

To all whom it may concern:

Be it known that I, JOHN W. GLEASON, a citizen of the United States, residing at Schenectady, in the county of Schenectady and State of New York, have invented certain new and useful Improvements in Spark Plugs, of which the following is a specification.

This invention relates to improvements in spark plugs.

An important object of this invention is to provide a spark plug having a novel form of intensifier arranged within the shell of the same and adapted for increasing the intensity of the spark at the sparking point of the plug so as to assure complete combustion of the fuel mixture within the cylinder of the motor to which the spark plug is attached.

20 A further object of the invention is to provide a spark plug having an insulator formed of upper and lower spaced sections between which is arranged an intensifier enclosed in an airtight chamber so that the current in making the gap in the intensifier will not be subjected to detrimental air currents.

30 A further object of this invention is to provide a spark plug having upper and lower insulator sections, the lower insulator section being substantially in the form of a sphere so that the same will expand and contract equally in all directions.

35 A further object of the invention is to provide a spark plug wherein the stationary electrode of the same has its free end portions widened and flattened to a thin edge so as to increase the efficiency of the spark upon making the final gap.

40 A further object of this invention is to provide a spark plug which may be readily taken apart for the purpose of cleaning the same.

45 Further objects and advantages of the invention will be apparent during the course of the following description.

In the accompanying drawing forming a part of this application, and in which like numerals are employed to designate like parts throughout the same.

Figure 1 is a vertical section through a spark plug embodying the invention.

55 Figure 2 is a group perspective of the insulator and the intensifier embodied in the invention.

Figure 3 is a fragmentary perspective of the spark plug.

In the drawing wherein for the purpose of illustration is shown a preferred embodiment of the invention, the numeral 5 generally designates one cylinder of an internal combustion engine provided, as illustrated in Figure 1, with the usual opening for receiving a spark plug. The improved spark plug forming the subject matter of this invention is provided with a shell 6 having its lower portion exteriorly screw-threaded, as indicated at 7, so that the same may be threaded into the spark plug opening of the cylinder. The upper portion of the cylindrical shell 6 is polygonal sided as indicated at 8, so as to form a gripping surface for a wrench whereby the plug may be applied and removed, as desired.

50 A substantially spherical insulator 9 of any proper material is arranged within the upper portion of the shell 6 and is provided with upper and lower annular shoulders 10 and 11, respectively, which are surrounded by annular gaskets 12. The lower gasket 12 is confined between the annular shoulder 11 and an interiorly arranged annular shoulder 13 formed by enlarging the upper portion of the shell. The upper gasket 12 is pressed into gas-tight engagement with the annular shoulder 10 and the adjacent portion of the shell by a nipple 14 which is threaded into the upper portion of the shell 8. By this construction the substantially spherical insulator 9 is securely but detachably held within the shell and is allowed to evenly and uniformly expand and contract as the result of the heat radiated from the motor.

55 As particularly illustrated in Figure 1, the upper insulator 15 is partly arranged within the upper portion of the nipple 14 and is limited in its downward movement by an interiorly arranged annular shoulder 16 having an annular gasket 17 mounted thereon for providing a gas-tight connection between the upper insulator 15 and the nipple. The upper insulator is held in rigid contact with the adjacent portion of the nipple by a ferrule or locking cap 18 having threaded engagement with the upper portion of the nipple and provided with an inwardly extending annular flange 19 having contact with the curved upper end of the insulator 15. The upper insulator is thus securely attached to the nipple 14 independ- 110

ently of the lower insulator so that each may partake of independent expansion and contraction as the result of heat radiated from the motor. The insulators are thus prevented from cracking or allowing the compressed gases to escape through the shell upon becoming heated.

The feed wire for the spark plug is provided with a terminal connection 20 adapted to be engaged with the upper terminal post 21 extended centrally through the upper insulator and having the usual binding screw 22 threaded thereon for securing the member 20 to the plug. The lower portion of the terminal screw 21 is provided with an enlarged head 23 which is seated in a centrally arranged recess in the lower portion of the upper insulator so that the outer side of the head is substantially flush with the under side of the insulator. A fastening nut 24 which is threaded onto the terminal screw 21, is drawn tightly into engagement with the upper side of the insulator so as to rigidly secure the terminal screw in position.

As illustrated in Figure 1, a cylinder 25 is confined between the opposed sides of the upper and lower insulators and is provided with a centrally arranged longitudinally extending opening 26 within which are upper and lower spherical members 27 and 28 respectively formed from any suitable metal. A metallic disk 29 is confined between the upper end of the cylinder 25 and the insulator 15 and is provided in its upper side with a recess partly receiving the head 23 of the screw 21 so that lateral movement of the disk is impossible. The upper spherical member 27 is in contact with the lower spherical member and is arranged in spaced relation to the disk 29 so as to provide a gap over which the electric current must jump before reaching the sparking point of the plug. In thus jumping the gap between the upper spherical member 27 and the disk 29, the spark at the sparking points is greatly intensified so that practically every particle of gas within the cylinder to which the spark plug is attached is ignited. This results in the smoother operation of the motor and the increased power and efficiency of the same. Also in intensifying the spark of the spark plug the accumulation of carbon on the electrodes of the plug and within the cylinders is reduced to a minimum.

The disk 29 confined between the upper end of the cylinder 25 and the adjacent portion of the upper insulator provides an airtight connection between the cylinder 25 and the upper insulator. The lower end of the cylinder 25 is mounted upon a metallic disk 30 which by reason of being forced rigidly into contact with the upper side of the lower insulator provides a gastight connection between the lower end of the cylinder 25 and the lower insulator. By this construc-

tion the cylinder 25 is securely held in position and an airtight space is provided within the cylinder with the result that the current in making the gap is not subjected to any objectionable air currents or subsequent changes in temperature. The disk 30 is provided with a centrally arranged hollow head 32 snugly receiving the upper end of the lower electrode 33 extended centrally through the lower insulator. The current is passed through the lower spherical member 28 and since said spherical member is mounted directly upon the upper end of the head 32, the current is of course transmitted through the head to the electrode 33. Both of the disks 29 and 30 are formed with annular flanges 30' which extend about the sides of the cylinder 25.

It will be noted with reference to Figure 1 that the cylinder 25 is spaced inwardly from the side walls of the nipple 14 for forming an annular air chamber 35 about the intensifier for maintaining a substantially uniform temperature at the intensifying gap.

The lower end of the shell carries a stationary electrode 36 which, as illustrated in Figure 3, has its forward end arranged in spaced relation to the lower end of the electrode 33 for providing the final spark gap of the spark plug. The stationary electrode 36 is disposed radially with relation to the longitudinal axis of the shell and has its free end portion flattened and tapered to an edge to form a knife-like edge alongside the electrode 33, with the result that the intensified spark may freely jump from the lower end of the electrode 33 to the knife-like edge of the electrode 36.

In assembling a spark plug constructed in accordance with this invention, the lower insulator is first arranged within the shell and is secured within the same by threading the nipple 14 firmly into contact with the upper end of the insulator 9. The cylinder 25 is then mounted upon the upper end of the lower insulator so that the hollow head 32 of the disk 30 will be caused to receive the upper end of the vertical electrode 33. The upper insulator is now arranged within the upper portion of the nipple 14 and is rigidly secured to the same by the ferrule or cap 19.

As set forth above and as illustrated in the drawing, the enlarged head 23 of the terminal screw and the disk 29 are spaced from the upper spherical member 27 so as to provide a gap over which the spark must jump to reach the firing point of the plug.

With reference to the foregoing description taken in connection with the accompanying drawing it will be apparent that a spark plug constructed in accordance with this invention may be readily taken apart for the purpose of cleaning or for replacing

any of the parts which may become broken as the result of continued use or an accident.

Further, the improved spark plug in manufacture is not appreciably larger than the 5 spark plug now generally in use and will not therefore be rendered difficult to apply or remove.

It is to be understood that the form of the invention herewith shown and described is 10 to be taken as a preferred embodiment of the same and that such minor changes in construction and arrangement of parts may be made as will remain within the spirit of the invention and the scope of what is 15 claimed.

Having thus described the invention, what is claimed as new is:

1. A spark plug including a shell, an insulator arranged within the same, a cylindrical nipple threaded into the upper portion 20 of the shell and securing said insulator in position, a second insulator secured to the upper portion of said nipple, upper and lower conductors carried by said first and 25 second named insulators and having their adjacent ends arranged in spaced relation, a cylindrical member confined between the opposed sides of said first and second named insulators and having a longitudinally extending bore, said cylindrical member being 30 arranged in spaced relation to the sides of said nipple for forming an outer annular chamber, and contact elements arranged within the bore of said cylindrical member. 35 2. A spark plug including a shell, a lower insulator arranged within the same, an upper insulator arranged in spaced relation to said first named insulator, a metallic disk mounted upon the lower insulator and having 40 a centrally arranged head, a conductor

extending through said lower insulator and engaged with the head of said disk, an intermediate insulator confined between the first and second named insulators and having one end engaged with said disk, and contact 45 elements arranged within said intermediate insulator.

3. A spark plug including a shell, an insulator arranged within the shell, a nipple threaded into the shell for securing the insulator in position, an upper insulator having its lower portion secured within the upper portion of said nipple, a ferrule threaded onto the upper portion of the nipple and having an inwardly extending flange in contact with the upper side of said upper insulator, a terminal post extending through the upper insulator and terminating at the inner end of the same, an intermediate insulator of cylindrical formation arranged between the first and second named insulators, a metallic disk mounted upon the upper end of the first named insulator and having a centrally arranged hollow head, a pair of contact elements arranged within said intermediate insulator and having electrical contact with the centrally arranged head of said disk, one of said elements being arranged in spaced relation to the inner end of said terminal post, said intermediate insulator being spaced inwardly from the sides of said nipple for providing an annular air chamber whereby a uniform temperature is maintained within said intermediate insulator, and an electrode carried 75 by the first named insulator and having its upper end snugly arranged within the centrally arranged head of said disk.

In testimony whereof I affix my signature.
JOHN W. GLEASON. [L. s.]
